SELF-REVERSING MAGNETIC SWITCH

Freland M. Murphy, Houston, Tex.

Application September 23, 1940, Serial No. 357,971

7 Claims. (CL 200—87)

My invention relates to improvements in magnetic switches.

An object of the invention is to provide a magnetic switch operated by a push button in a low voltage circuit, and in which the armature of the magnet operates a liquid contact circuit closure for closing a high voltage circuit and the same held in closed position until the button is again pushed when the circuit will be opened.

Another object of the invention is to provide a switch of this character in which the liquid contact circuit closure is held in its open and closed position by spring means, said spring means closing a circuit for a signal in the low voltage circuit to indicate the switch is closed and to break the circuit when the switch is opened.

A further object of the invention is to provide a switch of this character, in which the parts can be assembled in a casing in compact form, so that access may be readily had to all of the parts for replacement and repair. At the same time, means is provided for readily attaching or detaching the housing to the desired support.

A still further object of the invention is to provide a simple and effective switch of this character which can be cheaply manufactured and assembled with certain details of structure and operation hereinafter more fully set forth.

In the accompanying drawing:

Fig. 1 is a top plan view of my improved switch, showing the cover plate for the housing removed;

Fig. 2 is a longitudinal sectional view, taken on the line 2—2 of Fig. 1;

Fig. 3 is a transverse sectional view, taken on the line 3—3 of Fig. 1;

Fig. 4 is a view similar to Fig. 3, showing the switch operating mechanism in an open position;

Fig. 5 is a transverse sectional view, taken on the line 5—5 of Fig. 1, looking in the direction of the arrow;

Fig. 6 is a perspective view of the armature, showing the attachment of the switch operating arm thereto.

Referring now to the drawing, 1 represents a housing, which, as shown, is of rectangular form, with its rear edge 2 provided with laterally extending apertured ears 3 and 4, by means of which the same may be attached to a support. The upper end of the housing is closed by a removable cover 5, whereby access may be readily had to the housing; and, as shown in Figure 1 of the drawing, all of the parts are accessible for

repairs or replacement. The bottom of the housing is provided with a support 6, adapted to support the magnets 7 and 8. The bottom of the housing is also provided with ears 9 and 10, between which is pivoted the tongue 11 of the armature 12. This armature, as shown, is of a broad form to extend across the ends of the magnets 7 and 8 normally spring held in the position shown in Figure 2 of the drawing. The magnets 7 and 8 are arranged in a low voltage circuit which comprises the wires 13 and 14, connected to the binding posts 15 and 16, having wires 17 and 18 connected thereto.

The armature 12 has riveted thereto, by means of rivets 19, the switch operating arm 20, which extends between the magnets, as fully shown in Figures 1 and 2 of the drawing, a considerable distance beyond the rear ends thereof. The bottom of the housing, in rear of the magnets, is provided with a partition 21, having a bracket 22 on one wall thereof, and forms a bearing for the oscillating shaft 23, as fully shown in Figure 2 of the drawing. This partition 21 also serves to separate the high voltage circuit components from the low voltage circuit and thus remove any possibility of interconnection between the two circuits. The shaft 23 carries at its outer end a mercury tube 24, in which is arranged a body of mercury 25, as shown in Figure 5 of the drawing. Extending within one end of the mercury tube are the spaced terminals 26 and 27, which are connected to the wires 28 and 29, leading to the plug 30 of the high voltage circuit. The opposite end of the oscillating shaft 23 has rigidly connected thereto the cam member 31. The cam member 31 is of wedge shape with slanting walls 32 and 33, terminating in upwardly curved lugs 34 and 35. The lower end of the cam is of circular form, and provided with curved depressions 36 and 37. The depression 37 is of greater depth than the depression 36. Carried by the bottom of the housing is a standard 38 provided with a horizontally arranged arm 40. Above the arm 40, the standard carries a second horizontal spring arm 41, which has its outer end curved, as indicated at 42, adapted to enter the depressions 36 and 37, whereby the cam is held in its two positions. The arms 40 and 41 are provided with contact points 43 and 44. Connected to the arms 41 and 40 are the wires 45 and 46 leading to the pilot light 47, whereby the contact points are brought together to complete the circuit when the curved portion of the arm 41 is in the shallow depression 36.

The push button 48 is in circuit with the wire

17 and the wire 18, leading to the pilot light 41. The pilot light is connected by means of a wire 40 to the post 50, which has its lead wire 51 connected thereto. This wire 51 leads to the end of the spring arm 41. The end of the armature arm 20 is rounded, as indicated at 52 and extends above the cam 31, as shown in Figures 3 and 4 of the drawing. In the downward movement of the arm 20 the rounded end 52 engages the slanting walls 32 and 33 of the cam 31, and travels downwardly until it engages the lugs 34 and 35 and rocks the cam so as to oscillate the shaft 23 for moving the mercury tube 24.

In operation, it will be seen that, upon the pressing of the button 48, the circuit to the magnets will be closed and the armature rocked to bring the arm 20 down against the cam, rocking the cam, which in turn tilts the mercury tube for opening the circuit, as shown in Figure 5 of the drawing. When the push button is released, the spring causes the armature to resume its normal position shown in Figure 2 of the drawing. Pushing the button again causes the arm 20 to engage the cam and rock it in the position shown in Figure 3 of the drawing, thus tilting the mercury tube so that the mercury therein will contact the terminals 26 and 27, completing the circuit in the high voltage line. When in this position, the contact points 43 and 44 are in engagement for completing the circuit to the pilot light 41. Again pushing the button, the cam is rocked in the opposite direction and the mercury tube is tilted so that the mercury therein flows to the opposite end away from the terminals 26 and 27, and the circuit in the high voltage line is broken.

What is claimed is:

1. An electric switch, comprising a magnet, a circuit for the magnet, an armature operated by the magnet, an oscillating cam operated by the armature, a circuit closure operated by the shaft of the cam, and a combined spring detent and circuit contact engaging the cam and holding it in its two adjusted positions.

2. An electric switch, comprising a magnet, a circuit for the magnet, a spring held armature operated by the magnet, an oscillating cam operated by the armature, a liquid container circuit closure carried by the shaft of the cam, and a combined spring detent and circuit contact engaging the lower end of the cam and holding it in its two adjusted positions.

3. An electric switch, comprising a magnet, a circuit for the magnet, a spring held armature

operated by the magnet, an oscillating cam having a V-shaped upper end engaged by the armature for rocking the same in two directions, a circuit closure operated by the shaft of the cam, and a combined spring detent and circuit contact engaging the lower end of the cam and holding it in its two adjusted positions.

4. An electric switch, comprising a magnet, a circuit for the magnet, an armature operated by the magnet, an arm carried by the armature, a V-shaped oscillating cam having notches and adapted to be engaged and rocked by said arm, a circuit closure carried by the shaft of the cam, and a combined spring detent and circuit contact engaging the lower end of the cam and adapted to enter said notches for holding the cam in its two adjusted positions.

5. An electric switch, comprising a magnet, a circuit for the magnet, an armature operated by the magnet, an arm carried by the armature, an oscillating V-shaped cam having recesses in the lower edge thereof and positioned below the free end of the arm and adapted to be operated by the downward movement of the arm, a circuit closure operated by the shaft of the cam, and a combined spring detent and circuit contact adapted to enter said recesses for holding the same in its two adjusted positions.

6. An electric switch, comprising two spaced magnets, a circuit for said magnets, a pivoted armature operated by the magnets, an arm carried by the armature and extending between the magnets, an oscillating V-shaped cam having recesses in the lower edge thereof and positioned below the free end of the arm and adapted to be operated by the downward movement of the arm, a circuit closure operated by the shaft of the cam, and a spring detent and circuit contact adapted to enter said recesses for holding the cam in its two adjusted positions.

7. An electric switch, comprising two spaced magnets, a circuit for said magnets, a pivoted armature operated by the magnets, an arm carried by the armature and extending between the magnets, an oscillating V-shaped cam having a segmental lower end with spaced depressions and adapted to be operated by the engagement of the arm in its downward movement, a circuit closure operated by the shaft of the cam, and a combined spring detent and circuit contact adapted to enter the depressions in the lower edge of the cam for holding the same in its two adjusted positions.
